1,972,506

PRINTING PRESS

Henry A. Wise Wood, New York, N. Y., assignor
to Wood Newspaper Machinery Corporation,
New York, N. Y., a corporation of VirginiaApplication February 20, 1931, Serial No. 517,139
Renewed July 28, 1933

10 Claims. (Cl. 270—5)

The present invention relates to web presses and has for an object to provide a novel arrangement of printing units.

The invention relates more particularly to means for manufacturing newspapers with certain pages printed in multiple colors and others in single colors.

An object of the invention is to provide means for slitting a multi-color web into a plurality of ribbons and distributing the ribbons at will among a plurality of single-color webs.

In a copending application Serial No. 517,138, filed February 20, 1931, I described a web printing press comprising a plurality of single-color perfecting press units and a pair of multi-color press units adapted to print a perfected multi-color web, with means for slitting the latter and assembling the slit portions with the single-color webs and in any desired position with respect to said webs, after which the assembly of webs is passed through a folder to produce a unitary product. In the present application, I disclose a different arrangement of printing units wherein a plurality of single-color perfecting press units are arranged in line and a plurality of multi-color printing units are disposed in a line at right angles thereto. Means are also provided for bringing the webs from the two lines of press units into common alinement, with the multi-color webs distributed at will among the single-color webs.

Whereas, in said copending application the multi-color units are disposed above the single-color units, in the present application I disclose a construction in which all of the printing units are disposed upon the same level, thereby reducing the overall height of the press.

Another advantage of the present construction is the fact that the multi-color web does not have to be passed above the bank of single-color webs, as in said copending application, but may be introduced into said bank from the side at any desired level. Another object of the invention is to provide means for slitting the multi-color web into a plurality of ribbons and introducing each ribbon into the bank at any desired level. Whereas, in said copending application, means are provided for introducing the colored web ribbons at any desired order in the bank of single-color webs, the present invention includes a structure in which the colored web ribbons are led in a direct line to a folder and the single-color webs are slit, distributed at will among said ribbons, and turned into alinement therewith.

Other objects and advantages of the present

invention will appear in the following description of two embodiments thereof and thereafter the novelty and scope of the invention will be pointed out in the claims.

In the accompanying drawings:

Figure 1 is a somewhat diagrammatic view of a preferred arrangement of single-color and multi-color printing units;

Fig. 2 is a diagrammatic end elevation, on a larger scale, looking in the direction of the arrow 2, in Fig. 1;

Fig. 3 is a diagrammatic plan view of a modified arrangement of single-color and multi-color press units; and

Fig. 4 is a somewhat diagrammatic side elevation, on a larger scale, looking in the direction of the arrow 4 in Fig. 3.

The web press shown in Figs. 1 and 2 comprises a plurality of perfecting press units A, B, C, D and E, and a pair of multi-color press units F and G. Each perfecting press unit comprises a pair of printing couples 10 and 11 and 12 and 13, whereby webs passed successively through these couples will receive a single-color impression on each face thereof. It will be understood, however, that the color of the impression on one face may be different from that on the other, if so desired. Each of the perfecting press units is driven by an overhead motor 14 through a chain belt 15, as shown in Fig. 2. Means, not shown, but well known in the art, are provided for keeping the units A to E in perfect register.

The webs from the units A to E respectively, are carried up to an assembling mechanism indicated generally by the reference numeral 16, in Fig. 2, and each web passes over an individual drag roll 17 (Fig. 1) where it is cut by a slitting roll 18 into two half webs. Angled turning bars 19 and 20 are provided for turning the half webs at one side of the center line under and into alinement with half webs on the other side. These turning bars may be disposed in such angle that the half webs at the right hand side will be turned under and alined with those on the left hand side, or vice versa.

From the assembling mechanism the webs are led over a drag roll 21 to either or both of a pair of folding forms 22 and 23. In Fig. 2, a bank of ten half webs are shown, each pair of these coming from one of the units A to E. Thus, the half webs from the unit A are indicated by the numeral A¹ and A², those from the unit B, by the numerals B¹ and B², etc. It will be observed that the half webs in the bank are disposed in spaced superposed relation to permit of introducing the multi-

color webs therebetween, as desired, and as will be explained hereinafter.

The pair of multi-color units F and G are arranged in line at right angles to the line of perfecting press units A to E. Each multi-color unit, as shown in Fig. 2, comprises a single impression cylinder 25 about which are disposed four plate cylinders 26, 27, 28 and 29. Each plate cylinder is provided with its individual inking mechanism, indicated generally by the reference numeral 30. The two-multi-color units are powered by a single motor 31 mounted between them and arranged to run synchronously with the motors 14 so as to maintain the desired register between the single color and multi-cover webs. A pair of belts 32 and 33 are driven by the motor 31 and run to sprocket wheels 34 and 35 respectively, on the shafts of the two impression cylinders 25. These sprocket wheels, however, are not fixed to said shafts but drive the shafts through suitable reversing gear indicated at 36 and 37 respectively, in Fig. 1.

A web M which is to receive the multi-color impressions is led in counter-clockwise direction about the impression cylinder 25 so as to receive four impressions from the plate cylinders 26, 27, 28 and 29. Thence the web M is led about the impression cylinder 25 of the unit F in clockwise direction so that multi-color impressions are made on the opposite side of said web. From the unit F the web M passes about a drag roll 38, where it is cut into four ribbons by means of three slitter rolls 39. The ribbons are indicated by the numerals M¹, M², M³ and M⁴. By means of angle bars 40, 41, 42 and 43, the ribbons M¹, M² and M³ are brought into vertical alinement with the ribbon M⁴. Suitable compensating rolls 45 are provided for bringing all of said ribbons into mutual register.

The ribbons are now introduced among the webs A¹ to E² respectively, in any order desired. To this end, a plurality of guide rolls 46 are provided, there being a guide roll above and below the level of each of the single-color half webs in Fig. 2. In the arrangement shown in Fig. 2, the ribbons M¹, M², M³ and M⁴ are introduced between the half webs C¹, C², D¹, D² and E¹. Suitable turning bars 47 are provided above and below each of the half webs A¹ to E², whereby said ribbons may be turned into alinement with the half webs and be led with said webs to the folder 22 or 23 as the case may be. Obviously, the ribbons M¹ to M⁴ need not be shifted into vertical alinement if it be desired to transpose the relative levels of the ribbons in the bank of single-color webs. The turning bars 47 may then be adjusted as necessary.

In the construction shown in Figs. 3 and 4, the arrangement is somewhat different. Again we have a set of single-color press units N and O and a pair of multi-color units P and Q arranged in line but at right angles to the line of single-color units. The multi-color units are of the same general type as the multi-color units F and G and are driven by a common motor 50, as indicated in Fig. 4. A reversing clutch 51 is provided for each unit so as to permit of passing the multi-color web through said units in either direction.

In the arrangement indicated in Fig. 3, a single web passes through the units Q and P in succession and then is slit by means of slitter rolls, not shown, into a plurality of ribbons R¹, R², R³ and R⁴. The ribbons R¹, R² and R³ are folder under and into alinement with the ribbon R⁴ by means

of suitable turning bars, not shown. The position of the ribbons is clearly indicated in Fig. 4.

A pair of webs S and T are led through the single-color printing units N and O respectively, and carried over individual drag rolls 52 and 53. Slitter rolls 54 and 55 respectively, slit the web S into a pair of half webs S¹ and S² and the web T into a pair of half webs T¹ and T². A pair of turning bars 56 and 57 carry the web S¹ under and into alinement with the web S². Similarly, a pair of turning bars 58 and 59 carry the half web T¹ under and in alinement with the half web T².

A series of guide rolls indicated generally by the numerals 60 and 61 are provided to lead the half webs to any desired position with respect to the ribbons R¹ to R⁴. In the construction shown in Figs. 3 and 4, the web T¹ is led over a ribbon R⁴ and is then turned at right angles into alinement with said ribbon by means of a turning bar 62. The web T² is similarly brought between the ribbons R¹ and R³ and alined with said ribbons by a turning bar 63. Similarly, the half webs S¹ and S² are introduced respectively above and below the ribbon R² and brought into alinement therewith by means of turning bars 64 and 65 respectively.

By the arrangement just described, it is possible to lead the half webs from the single-color press units to any desired position in a bank of web strips or ribbons from the multi-color press units. Rolls 61 and turning bars 62 to 66 inclusive are provided to permit of introducing the webs from the single-color units into the bank of color ribbons at any level desired.

In Fig. 3, the ribbon R⁴ is not laterally diverted and all the rest of the ribbons are brought into vertical alinement therewith; but the arrangement could be varied so that any other ribbon would run to the folder without lateral divergence and one or more of the remaining ribbons would be brought into alinement therewith. For this reason, additional turning bars, indicated generally by the reference numeral 67, may be provided, whereby the webs from the single-color press units may be turned into alinement with any of the ribbons R¹ to R⁴, as desired. After the webs from the single-color units have been assembled with the web sections from the multi-color unit they are led into a folder 70, Fig. 3, so as to produce a unitary associated product.

While I have described two embodiments of my invention, it will be understood that these are to be taken as illustrative and not limitative and that I reserve the right to make such changes in form, construction, and arrangement of parts as may come within the spirit and scope of the following claims.

I claim:

1. In a web press, a folder, a plurality of single color press units aligned therewith, means for feeding webs from said units to the folder, a pair of multi-color press units disposed substantially at right angles to the single color units, and means for leading a web through the multi-color units and assembling said web in any desired order with the webs from the single color units to be fed therewith to the folder.

2. In a web press, a folder, a plurality of single color press units aligned therewith, means for feeding webs from said units to the folder, a pair of multi-color press units disposed substantially at right angles to the single color units, means for leading a web through the multi-color units, means for slitting the latter web into a plurality

- of ribbons, and means for distributing said ribbons at will among the webs from the single color units to be fed therewith to the folder.
3. In a web press, a folder, a plurality of single-color press units alined therewith, means for slitting the webs from said units into strips, means for bringing the strips into vertical alinement, a pair of multi-color press units disposed substantially at right angles to the single color units, one of the multi-color units being reversely movable with respect to the other, means for leading a web through said multi-color units to receive impressions on opposite faces thereof, means for slitting the latter web into a plurality of ribbons, means for distributing said ribbons at will among said strips, and means for feeding the strips and ribbons as a unit to the folder. 80
4. In a web press, a folder, a multi-color press unit alined therewith, means for passing a web through said unit, means for slitting the web into a plurality of ribbons, means for turning said ribbons laterally into vertical alinement, means for feeding the ribbons to the folder, a single color press unit disposed substantially at right angles to said ribbons, and means for leading a web from the single color unit above or below any one of said ribbons and turning the web into alinement with the ribbons to be fed therewith to the folder. 95
5. In a web press, a folder, a multi-color press unit alined therewith, means for passing a web through said unit, means for slitting the web into a plurality of ribbons, means for turning said ribbons laterally into vertical alinement, means for feeding the ribbons to the folder, a single color press unit disposed substantially at right angles to said ribbons, means for slitting a web from the latter unit into part-width webs, and means for distributing said part-width webs at will among the ribbons to be fed therewith to the folder. 100
6. In a web press, a folder, a row of printing units alined therewith, another row of printing units disposed at an angle to the first row, one of said rows including a multi-color unit, and means for associating and feeding webs from both rows as a unit to the folder, said means including means for slitting the web from the 110
- multi-color unit into a plurality of ribbons and for interleaving said ribbons at will among the rest of the webs.
7. In a web press, a folder, a row of printing units alined therewith, another row of printing units disposed at an angle to the first row, one of said rows consisting of single color units for perfecting a plurality of webs in single color and the other row comprising a pair of multi-color units for perfecting a web in multi-color, means for slitting the latter web into a plurality of ribbons, and means for distributing said ribbons at will among the single color webs and feeding them therewith as a unit to the folder. 120
8. In a web press, a pair of printing couples for perfecting a web in single color, a pair of multi-color units for perfecting another web in multi-color, the multi-color units being disposed at an angle to the printing couples, means for slitting the multi-color web into a plurality of ribbons, means for slitting the single color webs into a pair of half webs, means for bringing the ribbons and half webs into alignment and associating them in any desired relative position, a folder, and means for leading the associated ribbons and half webs as a unit to the folder. 130
9. In a web press, a folder, a row of printing units alined therewith, another row of printing units disposed at an angle to the first row, one of said rows consisting of single color units for perfecting a plurality of webs in single color and the other row comprising a plurality of multi-color units for perfecting webs in multi-color, means for distributing the multi-color webs at will among the single color webs and feeding them 140
- as a unit to the folder.
10. In a web press, a folder, a row of printing units alined therewith, another row of printing units disposed at an angle to the first row, one of said rows consisting of single color units for printing a plurality of webs in single color, the other row consisting of multi-color units for printing webs in multi-color, and means for distributing the webs from one roll at will among the webs from the other row and feeding them 150
- as a unit to the folder.
